UNITED STATES PATENT OFFICE.

HOWARD H. TALBOT, OF WOOSTER, OHIO, ASSIGNOR OF ONE-HALF TO LOUIS A. WOODARD, OF WOOSTER, OHIO.

APPARATUS FOR CUTTING HELICAL BEVEL TEETH.

Application filed September 1, 1921. Serial No. 497,493.

To all whom it may concern:

Be it known that I, HOWARD H. TALBOT, a citizen of the United States, residing at Wooster, in the county of Wayne and State 5 of Ohio, have invented certain new and useful Improvements in Apparatus for Cutting Helical Bevel Teeth, of which the following is a specification.

My invention refers to the art of cutting 10 gear teeth, and more particularly the cutting of helical teeth, either single or double, in bevel gears. Such forms of teeth bear a relation to the ordinary straight teeth of bevel gears similar to that which the helical 15 teeth of cylindrical gears bear to the straight teeth of ordinary spur gears. The cutting of helical teeth is accomplished by the use of a rotating end milling cutter, the axis of which is approximately normal to the elements 20 of the pitch cone of the gear, which cutter travels in a rectilinear path preferably towards the cone center of the gear. In order to effect the diagonal or helical cut across the face of the blank, the gear blank 25 is rotated in synchronism with such travel or feed, whereby to effect a resulting curved, diagonal or helical tooth across the gear face.

In cutting single helical teeth, the rotation 30 of the blank is continuous, and for double helical teeth, the direction of rotation of the blank is reversed when the cutter is about midway across the face of the blank, thereby producing a reversed curve or helical cut, 35 with a resulting V-shaped or helical tooth.

By reversing the rotation of the blank at two or more points across its face, the form 40 of the teeth may be correspondingly varied as to the number of the alternating tooth sections, as hereinafter described.

While preferred practice involves the use 45 of a preliminary or roughing out cut first, and then a finishing cut to produce the final form of the finished tooth, it will be understood that in certain cases the finished tooth face may be made in a single cut. The invention involves means for accurately positioning and supporting the blank and for intermittently shifting and rotating it with 50 relation to the cutter, means for mounting and driving the cutter, an indexing mechanism providing for correct cutting of successive teeth around the face of the blank to

ensure proper spacing, and various other features of operation and mechanism, as 55 shall be more fully hereinafter set forth.

One preferred embodiment of a machine adapted to carry out the invention is shown in the accompanying drawings, in which:

Fig. 1 is a general plan view of the complete apparatus as assembled;

Fig. 2 is an enlarged plan view, partly in section, showing the operative mechanism of the cutter and gear blank adjusting drive mechanism;

Figs. 3 and 4 are detail plan views of the clutch shifting and lever controlling mechanism for effecting change in the direction of rotation of the gear blank;

Fig. 5 is a sectional detail view of one of 70 the lever controlling disks, taken on the line V—V of Fig. 4;

Fig. 6 is a sectional detail view in plan of the gear blank actuating and indexing mechanism;

Figs. 7, 8 and 9 are diagrammatic views showing the operation of the cutter with relation to the blank at successively advancing positions;

Fig. 10 is a detail plan view, partly in section, of the cutter mechanism in operative relation to the gear blank and its supporting and rotating mechanism;

Fig. 11 is a transverse sectional view 85 showing the drive transmission for the cutter mechanism, the section being indicated on the line XI—XI of Fig. 10;

Fig. 12 is a cross section indicated by the line XIII—XII of Fig. 10;

Fig. 13 is a transverse sectional view 90 showing the worm wheel quadrant for the gear blank and its actuating mechanism, on the line XIII—XIII of Fig. 10;

Fig. 14 is a transverse sectional view on the line XIV—XIV of Fig. 6;

Fig. 15 is a transverse sectional view on the line XV—XV of Fig. 10;

Fig. 16 is a detail vertical sectional view showing the clamping mechanism for the face plate on the line XVI—XVI of 100 Fig. 14;

Fig. 17 is a detail view in elevation showing the change speed gearing for the cutter and gear blank adjusting drive mechanism.

In general, the machine comprises, in addition to its main supporting frame, three 105

main operating units suitably connected and synchronized so as to cooperate in performing the several necessary functions. These are, a gear spindle and face plate support 5 and its parts, generally indicated by the letter A; a cutter and gear blank adjusting drive mechanism, generally indicated by the letter B; and a cutter mechanism C. These are mounted in operative relationship as 10 shown in the somewhat diagrammatic representation of Fig. 1, and I will now describe these several unitary or main elements and their parts in detail.

Referring to the unit A, *a* is the gear blank of a bevel gear upon which the helical teeth are to be cut in the manner indicated in Fig. 10. The blank is mounted by its hub on the expanding sleeve 2 of a tapered arbor 3 of spindle 4 and tightened 20 thereon by nut 5 on the threaded end of the arbor. The cone center of blank *a*, i. e., the radial pitch center of the teeth, is capable of adjustment with relation to the pivoted center *v* of the annularly swinging 25 frame of the cutter mechanism C, towards or from the pivotal center, on the axial center line *w*, *w*, of the gear blank and its supporting spindle. This provides for offsetting the cone center *t* more or less to 30 ensure the desired tapering depth of teeth by action of the milling cutter *c* in its radial movement across and through the face of the blank on the radial line *v'*, *v*, and in parallelism with the feed screw of the cutter mechanism C, as hereinafter described. The inner end of arbor 3 is preferably journalled in a supporting bearing 6 of the main frame 7, towards the cone center *t*. A face plate 8 is also provided, securely 40 bolted to the spindle and arbor, and may be used for chuck attachment of the gear blank when required by its size. Otherwise, the blank may be merely mounted and secured on the end of the arbor, as shown.

Spindle 4 is journalled or housed in a rotatably adjustable cylindrical sleeve 9, which in turn rests in bearings 10 extending upwardly from the main frame 7^a. A depending worm wheel quadrant 11 is bolted or otherwise secured to the inner end of sleeve 9 and a worm index wheel 12 is secured to the other end of spindle 4. The quadrant is for the purpose of securely clamping the face plate 8, when the face plate is used, to prevent any slippage or relative movement between the two, about the axis *w*, *w*, of the spindle. A further purpose of the quadrant is to fixedly connect with and effect intermittent forward and back 55 rotation of the blank during radial travel of the cutter, for the formation of the helical teeth, as hereinafter described. The function of the index wheel 12 and its associated change gear mechanism is to impart 60 rotation of the blank during radial travel of the cutter, for the formation of the helical teeth, as hereinafter described. The function of the index wheel 12 and its associated change gear mechanism is to impart 65 the desired periodical amount of rotation to

the blank to properly index or divide it, for each cutting operation and the desired number of teeth.

Quadrant 11, secured to sleeve 9, is provided at its upper portion with bolting extension 13 for a triangular shaped bracket 14 capable of fixed connection with the face plate and blank spindle, to hold the blank in fixed relation to the quadrant. Bracket 14 is provided with means for clamping and unclamping the blank so that it may be relatively shifted as successive series of teeth are cut around its face.

The bracket is provided with upper and lower holes 15-16, either of which may be used, depending on the size of the face plate, for extension therethrough of a bushing 17 through which extends a clamping bolt 18. Said bolt has a head 19 engaging the annular T slot 20 of face plate 8 and its shank extends through bushing 17. The threaded end of bolt 18 engages the hub of a quadrant nut 21 having an intervening bearing collar and adjusting set screws 22 therefor. The nut 21 is actuated by a toothed gear segment 23 engaged by double toothed rack 24 slidably mounted in bearing 25 on bracket 14, and having a fluid-actuated piston 26 in cylinder 27, also mounted on the bracket. The cylinder is provided with suitable valve controlled supply and exhaust connections whereby, upon application of pressure on the piston rod side of piston 26, nut 21 will screw up on bolt 18, thereby binding and securing the face plate and locking it against relative rotational movement. In like manner, application of pressure on the opposite side of the piston will release the face plate for rotative movement, the bolt head 19 sliding in the annular slot 20.

Face plate 8 is so constructed that an auxiliary face plate ring 8^a of increased diameter may be attached around it, with an annular slot 20^a coinciding with the center of outer bolt hole 15, as indicated in dotted lines, Fig. 14. Such extended face plate may be used for large diameter gears. In such case, bolt 18, with a left hand thread, and bushing 17 are mounted in hole 15, and a co-acting quadrant nut and its toothed segment are utilized, engaging the upper series of teeth of rack 24, as indicated in dotted lines. Spindle bearing support 7^a is slidably mounted on housing base 28 capable of adjustment with the gear blank towards and from the pivotal center *v*, on center line *w*, *w*, and of being secured in position by bolts 29, for proper setting of the gear blank. Such construction also provides for ample movement backwardly of base 7^a to admit of removal of the cut gear, placing of another blank, or other operations. The segment 11 and the supported blank *a* are actuated by worm 30 of shaft 31 mounted at one

end in thrust bearing 32 and at the other in bracket bearing 33. Said bearing has a housing 34 surrounding driven bevel gear 35 of shaft 31 and driving bevel gear 36 of spline shaft 37, the latter being in sliding driving engagement with the terminal gear 38 of the cutter and gear blank adjusting drive unit B.

Gear 38 has an extended hub 39 properly key-seated for engaging spline shaft 37 and journalled in bearing 40 of the frame of unit B. Gear 38 being thus fixed against lateral movement, shaft 37 may slide through it incidental to the movement of bearing support 7^a and shaft 37 will be in driving engagement with the gear at all positions. Gear 38 is driven by pinion 41 of shaft 42 of gear box b, and shaft 42 is driven by change gear 43 and intermediate idler 20 change gears 44, 45 from gear 46 of shaft 47. Gears 44 and 45 are adjustably mounted by stud 48 in the slot of a supporting arm 49 pivoted to the gear box b at 50, and provided with an arc slot 51 and a securing stud and nut 52. (See Fig. 17.) By this means, the arm is adjustable for the purpose of permitting the use of various sets of change gears as may be required.

Shaft 47 is provided with loose gears 53, 30 54, each having a clutch for connection with a sliding clutch 55 splined on the shaft 47 and adapted to operatively connect with one or the other, or to assume a neutral position. (See Sheet 2.) Gear 53 is geared 35 through idler gear 56 with pinion 57 and gear 54 is geared directly with pinion 58, both of which pinions are secured to drive shaft 59 which is coupled directly to the drive shaft 60 of motor 61 with intervening clutch 130. Thus, with constant rotational direction of shaft 59, shaft 47 will be driven in the same direction when clutch 55 engages gear 53 and in the opposite direction when the clutch engages gear 54. Also, starting 40 with shaft 60, it will be seen that power is transmitted in two distinct transmissions, one through shaft 59 and its connections to the feed of the table of cutter mechanism C, the other through shaft 37 and its connections as described, for actuating the rotation of the gear blank.

The end milling cutter c is mounted in a chuck 62 on the end of a rotating horizontal splined spindle 63, driven through gearing 55 64, 65, shaft 66, and suitable reducing gearing from motor 67. The spindle and its chuck and housing are slidably adjustable in supporting ways 68 arranged across a lower supporting table or frame 69, which is 60 itself movable in a transverse horizontal plane, to carry the spindle and its cutter towards and from the work. Adjustment of the spindle housing and its shaft is by screw 70 mounted in table 69 engaging threaded lug 71 and having a hand wheel 72

(Fig. 12), so that the cutter may be withdrawn axially from its cutting position, when desired.

Table 69 is slidably mounted on the supporting pedestal or bed 73, which in turn is mounted for radial adjustment around the vertical center line v, v, (Fig. 11) corresponding to center v (Fig. 10). It will be noted also that the pivoting center v, v, extends through the horizontal center line w, w, of the spindle 4 and its arbor. At its inner end, the bed 73 is supported by annular extension 73^c on the annular face 74 of supporting base 75 forming the main support for the cutter mechanism. The edge of annular support 74 may be suitably inscribed with an indicating scale to facilitate setting of the bed to the desired angle, with relation to the taper of the blank to be cut. At its outer portion, bed 73 rests by pedestal 76 on annular trackway 77 concentric with center v, to which it may be secured by bolts, as shown. A hand actuated pinion 78 engages annular rack 79 by which the bed may be swung around to the desired position, and there locked for operation.

The table 69 and the cutter are shifted towards and from the pivotal center by means of a threaded shaft 80 engaging a worm nut 81 located between embracing depending bearing lugs 82 of the table and the shaft is anchored at its other end by a thrust bearing 83 in a housing 84 extending from bed 73 at its inner end. Worm nut 81 may be locked in position for feeding the table by rotation of threaded shaft 80 through nut 81, held stationary by worm 85 of shaft 86 mounted in bearings 87 on the table, and provided with a hand wheel 88 and lock nut 89. By loosening the lock nut 89, the worm 85 may be used to rotate worm nut 81 to adjust the table on the threaded shaft, when stationary.

Shaft 80 is driven through worm gear 90 in housing 84 and worm 91 of shaft 92 mounted in bearings 93, 94, of bed 73. The bed is pivotally connected to base 75 on the pivoting center line v, v, by a stud 95, and shaft 92 is geared through gears 96, 97, with shaft 98, which shaft coincides with such center, providing for pivotal swinging of the bed. Motion is transmitted to shaft 98 from drive shaft 59 through bevels 99, 100, shaft 101, and bevels 102, 103 respectively. By this means, the cutter table is actuated at any position by feed screw 80 through the intermediate gearing directly from motor 61. By the mechanism just described, it will be seen that the cutter supporting mechanism may be accurately set to position for work with relation to the particular gear blank to be cut, and that the rotating cutter c will be fed in a radial path across the bevel face of the gear. The gear blank

itself, when clamped to the spindle or immovably connected with the face plate and segmental worm wheel quadrant, is partially rotated first forwardly and then backwardly at slow speed, during the advance of the cutter across its face, resulting in the formation of the helical teeth in the manner described.

The worm wheel quadrant, as shown, preferably extends equally on each side of the normal or initial position, the purpose of which is to provide for operation in either direction, depending on the direction of projection of the helical teeth.

In Figs. 7, 8 and 9, I show diagrammatically the progress of the milling cutter *c* across the face of the blank *a* on the radial line *v'*, *v*. During such time, the blank is rotated in the direction of the arrow, Fig. 7, until the cutter has advanced to the middle of the blank face, Fig. 8, when the blank is reversed for the remainder of the cut in the direction of the arrow, Fig. 9, finishing the cut. This change of movement is effected by shifting the clutch 55 from gear 53 to gear 54, or vice versa, because for a given direction or rotation of shaft 59 and feed of the cutter *c*, the blank will rotate in one direction when clutch 55 engages gear 53, and in the opposite direction when it engages gear 54. It is also necessary, of course, that in cutting the successive teeth that these points of reversal of the helix or apices of the teeth be always in exactly the same line concentrically around the gear blank.

To this end, means are provided within the gear box *b* as follows: On shaft 59 are secured two narrow faced pinions 104 and 105 which mesh respectively with gears 106 and 107. Each gear 106 and 107 is fixedly connected with sleeves or hubs 108 and 109 mounted to turn on a fixed shaft 110 extending across within the gear box. The adjacent ends of sleeves 108 and 109 have enlarged confronting disks or flanges 111 and 112, each of which is provided with a peripheral notch or recess 113 and 114 respectively. The ratios of gears 104—106 and 105—107 are such that the notches 113—114 will come into alignment, or into registering position with each other, only at certain times, say for example, at every twenty-fourth revolution of gear 106 and flange 111.

The clutch 55 is designed to be shifted, either manually or automatically, by a controlled lever 115 pivoted at 116 within the gear box *b* having a fork or shifting abutments 117 engaging the clutch and an extension 118 in working connection with an operating lever 119, extending upwardly through the top of the gear box.

Extending downwardly from the other end of lever 115 is a pin, roller, or abutment 120 of a diameter to interfit and slip through the notches 113—114 when they are in reg-

ister, and which, of course, will prevent the lateral operation of the lever except at such times. By this means, clutch 55 can only be shifted from gear 53 to gear 54, or vice versa, at such registering positions of the disks, one of which times occurs when the cutter *c* is midway of the face of the gear blank, as in Fig. 8.

This is because the notches come into register once only in say every twenty-four revolutions of gear 106, or at such other predetermined time, depending on the gear reduction used in the machine, so that reversal of the gear blank is correspondingly effected and controlled.

Therefore, with the machine set so that the clutch 55 can be shifted only when the cutter *c* is in the center of the face of the gear blank, it will be impossible to shift the clutch during any intermediate position of the cutter, or otherwise than at definite periodical positions of reversal, as say two, four, six, etc. inches beyond the midway position, since the assumed twenty-four revolutions of gear 106 and flange 111 corresponds to about two inches of the cutter. Such positions are well within the observation of the operator and no mistake could be made as to the midway position.

It will be understood, of course, that in the case of a Z-shaped or double involute W-shaped tooth, the rotation of the blank may be interrupted or reversed two or more times during the transverse travel of the rotating cutter, by the use of suitable gearing adapted to bring the notches 113—114 into register at such times, in the same manner as above described.

Shaft 59 is connected to shaft 60 by coupling 121 and is mounted in bearings 105 transversely across a second gear box *bb*. Freely rotatable on shaft 60 is a sleeve or bushing 122 having a clutch terminal 123 and a gear 124, keyed to the sleeve, is in mesh with driving pinion 125 of shaft 126. Shaft 126 is driven through gear 127 by pinion 128 keyed to shaft 129, which extends across into gear box *bb* from a third gear box *bbb*. The extended end of shaft 60 carries a double throw clutch 130 splined on the shaft and operable by lever 130^a to engage clutch terminal 123 of gear 124 or a similar clutch 131 of motor shaft 132. Shaft 129 is driven through clutch 133 through either of gears 134 or 135 mounted freely on the shaft, and each having a co-acting clutch 136 and 137.

Motor shaft 132 has a splined clutch 138, and, at each side thereof, freely rotatable pinions 139 and 140 each having a co-acting clutch 141 and 142 respectively. Pinion 139, when in clutch, drives gear 135 through idler gear 143 on shaft 144, and pinion 140, when in clutch, drives gear 134 through reduction idler gears 145—146, fixed together, but free

to rotate on shaft 144. Clutches 133 and 138 are operated by levers 147 and 148 respectively extending inwardly through the casing of gear box *bbb*.

5 By this arrangement of gearing and clutches, I am enabled to utilize the power of widely variable speed motor (61) whereby to transmit power to shafts 37 and 59 at approximately the desired speed, with regulation of the number of revolutions controlled by the change speed gearing provided.

10 For example, if the ratio of gear train 139—143—135 is 1:1, and ratio of gear train 140—145—146—134 is 1:4, and we have a variable speed motor 61 of 4:1 range, we have in combination a total selective speed range of 16:1 under control of the operator, according to the speed of the feed 20 required for the end milling cutter *c*.

15 It will be noted that the gearing of gear box *bb* provides for a constant ratio gear reduction. The result, in effect, is that with the variable gear trains in gear box *bbb* and the constant reduction train of gear box *bb* (the latter by engaging clutch 130 with clutch 123 of gear 124) either may be used during the working feed stroke of cutter *c*.

20 It will also be evident that by disengaging clutches 133 and 138 and engaging clutch 130 with clutch 131, shaft 60 will be driven directly by the motor. Such condition is utilized for the quick reverse action of the cutter *c* ready to begin the cutting of the next tooth. Return motion, of course, is effected by reversing the rotation of the motor.

25 The described operation of cutting the individual teeth on the gear blank is on the assumption that the gear blank is fixedly clamped to the face plate and through the face plate to the worm wheel quadrant 11. At the termination of each cutting operation, it is necessary, of course, to shift the blank around one pitch space to bring it into position for the next cut. I have provided indexing mechanism for such purpose, adapted to provide for successive cutting of the entire annular series of properly spaced 30 teeth around the blank.

35 To this end, the clamping bolt 18 is first released by operation of the fluid actuated rack bar 24 and nut segment 23, and the spindle 4 is then rotated to carry the blank around the desired distance by the following means.

40 Index wheel 12, being fixedly keyed to the outer end of spindle 4, is provided with annular worm teeth engaged by a worm 149 which is adapted to be turned to the proper degree by means of gears connecting its shaft with the indexing mechanism 150. The latter is of well known construction, and need not be described in detail, except to say that it involves the use of the usual

change speed gears between a driving pulley 151 and the worm 149, as will be readily understood.

45 Pulley 151 is driven by belt 152 from pulley 153 of shaft 154, which in turn is geared with a motor 155 through pulley 156, belt 157, pulley 158, and gearing 159.

50 The motor and its gearing and shaft 154 are mounted upwardly above the sleeve 9 upon a bracket 160 secured to the rear end 75 of the sleeve, while worm 149 and the indexing mechanism 150 are supported by a similar bracket 161, depending from the rear end of the sleeve, as in Fig. 6. These brackets and their supported parts normally occupy a vertical position at approximately right angles to the horizontal plane through the spindle axis, but for convenience of illustration are shown broken away from the spindle, and in their proper vertical position 80 in the plan view in which they are present.

55 These parts, being thus connected with the sleeve, will rock back and forth with it as the sleeve, quadrant, and gear blank are rocked back and forth by the worm 30 throughout each cutting operation. Also, when worm 30 is inactive, the quadrant and indexing mechanism supporting brackets are immovable. If the face plate 8 is used and the clamping bolt 18 is in release, the operation of motor 155 will drive the index mechanism and turn worm wheel 12 and the spindle 4 and arbor 3, or the arbor and face plate 8, so that rotation of the gear blank 100 independent of the relatively fixed quadrant 105 results.

60 By means of the stop latch disks 112 and suitable change speed gears of the index mechanism 150, the periodical amount of rotation of the blank is determined to properly index or divide it into the desired number of teeth.

65 The construction of my improved machine will be readily understood from the foregoing description. In general, its operation in carrying out the improved method of cutting helical teeth is as follows.

70 Assuming the gear blank has been mounted and chucked in proper position and the machine has been adjusted properly, involving correct location of the bearing support 7^a with relation to the center *v*, proper angular setting of the bed 73 for the cutter mechanism *C*, selection of proper indexing change gears and of the change gears for gears 43 and 46, the selection and affixing of a suitable cutter *c*, and that the several other necessary adjustments have been made, as described:

75 First withdraw the cutter *c* by hand wheel 72 to clear the face of the gear blank. Then make a trial run of motor 61 until the cutter is approximately at the center of the face of the gear blank and the notches 113—114 of disks 111—112 are in register,

so that clutch 55 may be engaged with either of the clutch gears 53 or 54, stopping the motor at such position. Then, by means of hand wheel 88 and worm gearing 85—81, adjust position of table 69 and the end milling cutter *c* to the exact position midway of the gear blank face, which corresponds to the point of reversal of the tooth helix. Now, secure lock nut 89 to fix worm wheel nut 81 against further rotation to ensure feed of the table by threaded shaft 80. Clutch 55 is then shifted to engage, for example, clutch of gear 53 which will give proper direction of rotation to the blank *a* for the initial part of the cutting operation.

Clutches 133 and 138 being in neutral position, throw clutch 130 into engagement with clutch 131 and by running motor 61 in reverse direction from that required for the forward stroke of the feed of table 69, return the cutter to a position clear of the back edge of the gear blank face. Then, by hand wheel 72 and screw 70, feed the cutter spindle towards the blank to proper cutting depth position, and engage clutches 133 and 138 with the desired selective gear train of gear box *bbb*, and engage clutch 130 with clutch face of sleeve gear 124. Start motor 61 at desired speed and also in rotational direction to give forward feed of cutter, and also start milling head motor 67 at proper speed to rotate the cutter *c*. The cutter will then enter the edge of the blank face and cut the tooth groove, the depth and width of cut gradually decreasing from the outside towards the center, due to the path of the cutter being on the radial line *v'*, *v*, and the offsetting therefrom of the cone center *t* of the gear blank.

When the cutter has reached the helical reversal point as described, the notches 113—114 will be in register, and motor 61 should now be slowed down and, if necessary, stopped at this stage of the operation. Then, shift clutch 55 into clutch of gear 54, speed up or start the motor again, and continue the cutting of the remainder of the helical tooth groove in the opposed direction.

When the cutter has finished the cut, stop motor 61, withdraw the cutter to clear the face of the blank, and with the motor driving direct for quick return, as described, withdraw and return the cutter mechanism to initial position at the outer edge of gear blank, ready for the next cut. The blank is then adjusted laterally one pitch space by the index mechanism to the next position, and the cutting operation is repeated, and these operations are continued until all the teeth are cut.

If the teeth are not finished by the initial cut, and are merely rough cut, a finishing end milling cutter may then be substituted and the teeth cut to finished size by repeat-

ing the series of cutting operations, as described.

The treatment of the blank in this respect is largely within the province and judgment of the operator, dependent on the size and other characteristics of the gear being cut. If it is necessary to cut one side only of each tooth at a time, the entire series of side cuts for one side of each tooth may be made around the face of the blank, and then the series of opposite side cuts, by using the machine in the manner described, and with proper adjustment of the indexing mechanism, as will be readily understood by those skilled in the art.

The machine as a whole provides for the cutting of helical teeth of bevel gears within a wide range as to size, number and shape of teeth, and other characteristics. It may be changed or varied in different details of construction or otherwise by the skilled mechanic within the scope of the following claims.

What I claim is:

1. A machine for cutting helical bevel gears having a rotatable blank support, means for alternately rotating the blank thereon forward and back, a rotating end milling cutter, a slidable support therefor, driving mechanism for the cutter on said support, a pivotally mounted laterally swinging table for the cutter support, and gearing for moving the cutter support thereon in a straight line movement during reversal of the blank.

2. A machine for cutting helical bevel gears having a rotatable blank support, means for alternately rotating the blank thereon forward and back, a rotating end milling cutter, a slidable support therefor, driving mechanism for the cutter on said support, a pivotally mounted laterally swinging table for the cutter support, gearing for moving the cutter support thereon in a straight line movement during reversal of the blank, and means for supporting the table and fixedly locating it in position.

3. In combination with an intermittently and oppositely rotatable gear blank support and actuating and indexing mechanism therefor, a laterally swinging pivoted table, means for adjusting and securing it in position, a longitudinally slidable cutter support thereon, a feeding screw engaging a nut on the cutter support, actuating gearing for the feeding screw, a rotatable end milling cutter on the support adapted to traverse the face of a gear blank in a straight line movement during reversal thereof, and means on the cutter support for driving the cutter.

4. In combination with an intermittently and oppositely rotatable gear blank support and actuating and indexing mechanism therefor, a laterally swinging pivoted table,

means for adjusting and securing it in position, a longitudinally slideable cutter support thereon, a feeding screw engaging a nut on the cutter support, actuating gearing 5 for the feeding screw, a rotatable end milling cutter on the support adapted to traverse the face of a gear blank in a straight line movement during reversal thereof, means on the cutter support for driving the 10 cutter, and means for adjusting the cutter.

5. Cutter supporting and driving mechanism for a gear cutting machine as described consisting of a laterally swinging pivoted support, means providing a carrying trackway therefor, a table slidably mounted on said support having a nut, a threaded shaft engaging said nut, gear mechanism for transmitting driving power to the threaded shaft through the pivoting 20 center of the laterally swinging support, and a longitudinally adjustable end milling cutter and driving means therefor mounted on the table.

6. Cutter supporting and driving mechanism for a gear cutting machine as described consisting of a laterally swinging pivoted support, means providing a carrying trackway therefor, a table slidably mounted on said support having a worm nut and bearings therefor, means for turning said nut and for locking it in position, a threaded shaft engaging the nut, gearing for actuating the threaded shaft at varying positions of the swinging support, and a longitudinally adjustable end milling cutter and driving means therefor mounted on the table.

7. The combination with the threaded shaft and slideable cutter table having a worm nut engaging the shaft between bearings on the table, of a nut-engaging worm and its spindle mounted on the table and provided with a hand wheel.

8. A gear cutting machine having a slideable cutter table, a cutter housing provided 45 with a rotatable end milling cutter and a splined spindle therefor, a motor, gearing in splined engagement with the cutter spindle for driving it from the motor, and means for adjusting the cutter housing and spindle on the table.

9. A gear cutting machine having a slideable cutter table, a cutter housing provided with a rotatable end milling cutter and a splined spindle therefor, a motor, gearing 55 in splined engagement with the cutter spindle for driving it from the motor, and an adjusting screw engaging a threaded portion of the cutter housing for adjusting it on the table.

10. Means for supporting and adjusting a gear blank with relation to a tooth cutter consisting of a blank supporting spindle, a rotatable sleeve therefor, means embodying 60 a releasable clamping bolt for flexibly connecting the blank with the sleeve and for re-

leasing it therefrom, and means for partially rotating the sleeve and blank.

11. Means for supporting and adjusting a gear blank with relation to a tooth cutter consisting of a blank supporting spindle, a 70 rotatable sleeve therefor, means embodying a releasable clamping bolt for flexibly connecting the blank with the sleeve and for releasing it therefrom, and means for partially rotating the sleeve and blank in alternating opposite directions.

12. Means for supporting and adjusting a gear blank with relation to a tooth cutter consisting of a blank supporting spindle, a 80 rotatable sleeve therefor, means for flexibly connecting the blank with the sleeve and for releasing it therefrom, and segment and worm gearing connected with the sleeve for partially rotating the sleeve and blank.

13. Means for supporting and adjusting 85 a gear blank with relation to a tooth cutter consisting of a blank supporting spindle, a rotatable sleeve therefor, a worm segment connected with the sleeve, a driving worm therefor, and releasable clamping mechanism 90 carried by the segment for fixedly connecting it with the gear blank.

14. Means for supporting and adjusting a gear blank with relation to a tooth cutter consisting of a blank supporting spindle, a 95 rotatable sleeve therefor, a face plate fixedly connected with the spindle having an annular clamping slot, an adjusting segment connected with the sleeve, a clamping bolt 100 engaging the slot, and actuating mechanism therefor carried by the segment.

15. Means for supporting and adjusting a gear blank with relation to a tooth cutter consisting of a blank supporting spindle, a 105 rotatable sleeve therefor, a face plate fixedly connected with the spindle having an annular clamping slot, an adjustable segment connected with the sleeve, a clamping bolt 110 engaging the slot, a nut therefor having a toothed segment, and a fluid actuated rack bar carried by the segment engaging the nut.

16. The combination with the spindle actuating face plate having an annular clamping slot and the sleeve-actuating segment and a bracket thereon; of a clamping bolt 115 engaging the slot by its head and extending through the bracket by a threaded terminal, a nut engaging the bolt and having a segmental toothed arm, a rack bar engaging the arm and provided with a piston, and a fluid-actuating cylinder therefor mounted on the bracket.

17. The combination with the spindle actuating face plate having an annular clamping slot and the sleeve-actuating segment 125 and a bracket thereon; of a clamping bolt engaging the slot by its head and extending through the bracket by a threaded terminal, a bushing therefor, a nut engaging the bolt and having a segmental toothed arm, ad- 130

justing set screws in the nut, and a fluid actuated cylinder, piston and rack bar mounted on the bracket and in operative engagement with the toothed arm.

5 18. Means for supporting and adjusting a gear blank with relation to a tooth cutter consisting of a blank supporting spindle, a rotatable sleeve therefor, means for fixedly connecting the blank with the sleeve and for releasing it therefrom, index mechanism for independently rotating the spindle and blank, and means for partially rotating the sleeve and blank.

15 19. In combination, a blank supporting spindle, a rotatable sleeve therefor, means for fixedly connecting the blank with the sleeve and for releasing it therefrom, means for partially rotating the sleeve and blank, means for independently rotating the spindle carried by the sleeve, and a longitudinally movable support for the sleeve.

25 20. In combination, a blank supporting spindle, a rotatable sleeve therefor, means for fixedly connecting the blank with the sleeve and for releasing it therefrom, means for partially rotating the sleeve and blank, means for independently rotating the spindle carried by the sleeve, and a longitudinally movable support for the sleeve having 30 a shaft geared with the sleeve rotating means and in sliding splined connection with a driving gear.

35 21. In combination, a blank supporting spindle, a rotatable sleeve therefor, means for fixedly connecting the blank with the sleeve and for releasing it therefrom, means for partially rotating the sleeve and blank, means for independently rotating the spindle carried by the sleeve, a longitudinally 40 movable support for the sleeve provided with sleeve bearings, a supporting base therefor, and means for securing the sleeve support to the base.

45 22. In combination with a rotatable blank reciprocating sleeve and a blank supporting spindle rotatably mounted therein and provided with an index wheel; supporting framework fixedly connected with the sleeve and means for actuating the index wheel 50 mounted thereon.

55 23. In combination with a rotatable blank reciprocating sleeve and a blank supporting spindle rotatably mounted therein and provided with an index wheel; a bracket depending from the sleeve provided with gearing engaging the index wheel, and a bracket extending upwardly from the sleeve having a motor in driving connection with said gearing.

60 24. The combination with a blank supporting spindle, a rotatable blank reciprocating sleeve, means for fixedly connecting and releasing the spindle and sleeve and a blank carried by the spindle and gearing 65 for rotatably actuating the sleeve; of an in-

dex wheel secured to the spindle and actuating gearing and driving mechanism therefor carried by the sleeve, whereby to impart independent rotatable movement to the spindle and blank.

70 25. In a machine for cutting helical teeth of bevel gears, means for reciprocably rotating the blank supporting mechanism and reversing the same at a predetermined point consisting of a main drive shaft, gearing for transmitting motion therefrom in opposing directions to the blank supporting mechanism embodying a direct driving and a reverse driving clutch, a shifting clutch therefor having a lever, and means controlled by the driving shaft for locking and unlocking the lever to ensure shifting thereof at a predetermined time.

75 26. In a machine for cutting helical teeth of bevel gears, means for reciprocably rotating the blank supporting mechanism and reversing the same at a predetermined point consisting of a reversing drive shaft, a power shaft, independent trains of gears between the reversing shaft and the power 90 shaft, each having a clutch, a co-acting clutch provided with an operating lever having a limiting abutment, and means in driving engagement with the power shaft providing clearance for said abutment at a pre- 95 determined time.

80 27. In a machine for cutting helical teeth of bevel gears, means for reciprocably rotating the blank supporting mechanism and reversing the same at a predetermined point 100 consisting of a reversing drive shaft, a power shaft, independent trains of gears between the reversing shaft and the power shaft each having a clutch, change speed gearing interposed between said gears and the reversing drive shaft, a shifting clutch adapted to engage either of said trains of gears for direct and reverse drive respectively, a shifting lever therefor having an abutment, and a pair of notched disks in 110 variable operative connection with the power shaft adapted to come into registering position at a predetermined time to provide clearance for the lever abutment and to permit shifting thereof.

115 28. Shift controlling mechanism for the clutch lever of a gear cutting machine consisting of a pair of confronting disks each having an annular recess, a clutch lever having an abutment adapted to pass through 120 said recesses when they are in register but to engage the face of either disk when in non-registering position, and a shifting clutch actuated thereby.

125 29. In combination with the reversing drive shaft of blank reciprocating mechanism of a gear cutting machine, and a clutch-controlled power driven shaft and a time controlled shifting lever therefor; change speed gearing interposed between the clutch 130

controlled shaft and the reversing drive shaft, substantially as set forth.

30. Power transmission mechanism for a gear cutting machine of the class described
5 adapted to actuate blank reciprocating mechanism and cutter mechanism respectively consisting of a line shaft and gearing connecting it with the cutter mechanism, clutch-controlled gearing connecting the line
10 shaft with the blank reciprocating mechanism, a driving motor, and clutch controlled gearing for transmitting power therefrom to the line shaft.

31. Power transmission mechanism for a
15 gear cutting mach'ne of the class described
adapted to act ate blank reciprocating mechanism and cutter mechanism respec-

tively consisting of a line shaft and gearing connecting it with the cutter mechanism, clutch-controlled gearing connecting the line
20 shaft with the blank reciprocating mechanism, a driving motor, a shifting clutch for direct connection between the line shaft and motor, a gear box and gearing interposed between said shifting clutch and the line
25 shaft, a gear box and clutch-controlled gearing interposed between the shifting clutch and the motor, and a shaft connecting the gearing of one gear box with that of the other whereby to provide for variable speed
30 drive of the line shaft.

In testimony whereof I hereunto affix my signature.

HOWARD H. TALBOT.
